UNITED STATES PATENT OFFICE

JAMES KELLEHER, OF CHIPPAWA, ONTARIO, CANADA, ASSIGNOR TO HARPER ELECTRIC FURNACE CORPORATION, A CORPORATION OF NEW YORK

ELECTRIC FURNACE RESISTOR

Application filed November 27, 1925. Serial No. 71,516.

This invention relates to a resistor adapted for use as a heating element of an electric furnace, and to the method of forming same.

Among the objects of my invention is to produce a resistor of this character which is highly efficient in operation, strong and durable in use, and which may be operated at a high temperature without deterioration, and without the necessity of enclosing the same in an air tight compartment to prevent oxidation.

In accordance with my invention, I employ a carbonaceous resistance element around which is moulded refractory material, which is inert with respect to the resistance element, and which has high heat conductivity. The refractory body, preferably, not only encloses the resistance element but also encloses a portion of the conductor terminals which are connected to the resistance element. While the refractory body encloses the resistance element, special provision is made to prevent breaking of the resistance element or the enclosing sheath due to differences in expansion of the resistance element and sheath when both are heated. Enclosing the refractory body is a coating of fused material which forms a seal to prevent access of gas through the refractory body to the carbonaceous resistance element, and in this manner prevents oxidation of the carbonaceous material when the resistor is operated in an oxidizing atmosphere.

In the preferred form of my invention, the refractory material is formed of silicon carbide, recrystallized in whole or in part, and the outer sealing coating is formed of fused borax.

In making up the resistor, a graphite or other carbonaceous resistance element of the zigzag type or other suitable form is employed. The usual conducting terminals are secured to the resistance element and the element and terminals are then coated with a readily fusible or volatilizable material such

as paraffin wax. The assembled coated resistance element and terminals are then placed in a mould which conforms to the outside shape of the finished body. The space between the assembled resistor and mould is then rammed with the body refractory. Any one of several mixtures may be employed. One such mixture is composed of sand and coke in such proportions that, when the resistor is connected to a source of electrical energy to heat it to a sufficiently high temperature, silicon carbide is formed. Again the so-called "carborundum firesand" which is silicon carbide in the amorphous state, may be used, and this material, when heated to a sufficiently high temperature, will crystallize forming silicon carbide. I prefer, however, to use a body refractory mixture composed of crushed silicon carbide grains because less time is occupied in preparing the resistor body for use once the resistance element and terminals have been moulded into the body. When crushed silicon carbide grains are employed, I preferably employ a mixture of coarse and fine grains because such mixture moulds better into the shape desired.

To whatever mixture employed, I add 1% to 15% by weight of borax, and then add enough water so as to make the mixture of such consistency that it can readily be rammed into the mould. The borax content depends upon the use for which the resistor is designed. The thickness of the body surrounding the resistance element and terminals depends upon the use for which the resistor is designed, and this thickness may vary between a very thin layer such as $1/8$ " to $1\frac{1}{2}$ " or even thicker.

Having finished moulding the body around the resistance element and terminals, the mould is removed from around the body and the whole is then dried out by passing current through the resistor. As the body dries out, the energy dissipated in the resistor is in-

creased until the whole has attained a white heat on the outside.

Upon cooling, the borax will be found to have melted forming a gas tight film on the

- 5 outside of the body, and when the mixture, composed of crushed silicon carbide grains has been employed, it will be found on trans-
verse fracture that the silicon carbide next to
the resistor is recrystallized forming a solid
10 or monolithic recrystallized silicon carbide
resistor sheath. Although recrystallization
is not essential, it is preferable. During the
heating operation, the wax coating on the
resistance element will have melted and the
15 wax seeped through the body of the sheath
leaving a space between the resistance ele-
ment and the silicon carbide sheath. This
space will eliminate any danger of cracking
the sheath or resistance element, due to dif-
20 ference in the expansion of the resistance ele-
ment and sheath when the resistor is heated
in use. As the silicon carbide sheath is an ex-
cellent conductor of heat, it permits the heat
to be transmitted from the resistor to the fur-
25 nace chamber with a minimum loss.

Another method of making one of these resistors complete with its case or protection, is to mould the silicon carbide around the coated resistance element and terminals as
30 described above, but without the addition of
borax. Instead of borax, glue or some other
temporary bond is mixed with the silicon car-
bide. The mould is then removed and the re-
sistor is dried out at a temperature just suffi-
35 cient to drive off the moisture used in mould-
ing the body. When sufficiently dried, the
whole is then placed in a furnace and sur-
rounded by a mixture of sand, coke and saw-
dust, similar to that used in making silicon
40 carbide. The terminals are then connected to
a source of electrical energy and the resistor
is run at sufficient energy consumption and
length of time to recrystallize part or the
whole of the body. When the furnace is
45 sufficiently cool, so as to permit the handling
of the resistor and terminals as a unit, it is
removed and any adherent silicon carbide
mixture is scraped off and the body cleaned.
A solution of borax and water is then poured
50 over the body. The body being porous, ab-
sorbs the solution readily. The proper
amount of borax being added in this manner
the moisture is again driven off by heating
carefully and slowly. When dried the re-
sistor is connected as before, to a source of
55 electrical energy until a white heat has been
attained, and then allowed to cool off. The
resistor is now ready to be placed in any fur-
nace adapted for its use.

60 An advantage of this type of resistor is
that no special chamber need be built for the
resistor so as to exclude oxygen. The resistor
may be operated in an atmosphere which is
highly oxidizing without deterioration.

65 Furthermore, due to the strength of the heat-

ing unit, comprising the resistor and termi-
nals, it may be placed in any convenient posi-
tion in the furnace. Electrical connection to
the resistor may be made outside the furnace
and in case of failure or fracture, the resist-
70 ance element, terminals and refractory may
be removed as a unit and readily replaced
by a spare unit.

75 By the use of the zigzag type of carbona-
ceous heating element, it is possible to have
a resistor of large energy dissipating qual-
ities, confined to a small space thus permitting
high furnace temperatures, which may be ob-
80 tained in a very short space of time. It will,
however, be understood that if desired, other
85 forms of carbonaceous resistance elements
may be used.

90 In the accompanying drawings, Fig. 1
shows partly in elevation and partly in cen-
tral longitudinal section, a heating unit con-
structed in accordance with one form of my
invention, and Fig. 2 shows a fragmentary
95 transverse section of this unit taken on the
line 2-2 of Fig. 1. In the drawing, 10 repre-
sents a zigzag graphite or other carbonaceous
resistance element to which is secured in any
100 suitable manner conducting terminals 11. The
resistance element and terminals are em-
bedded or incased in the refractory body ma-
terial 14, which, as shown, envelops the en-
tire outer surface of the resistance element.
105 It does not penetrate the slots in the zigzag
element, and is slightly spaced from the outer
surface of the resistance element and termi-
nals as is indicated at 13 except at the outer
110 ends of the terminals 11 where the sheath is
in direct contact with the surface of the ter-
minals. The outer surface of the refractory
material 14 is sealed by a coating or film 15
of fused borax. While the drawing shows
115 the borax as forming a film on the outside of
the surface of the refractory material, it will
be understood that borax may penetrate to
some extent the refractory material serving to
120 fill the pores or interstices in the surface of
the refractory body.

I claim:

1. A resistor comprising a carbonaceous re-
sistance element incased in a monolithic mass
of silicon carbide, said mass being slightly
115 spaced from the surface of said resistance ele-
ment so as to independently expand and con-
tract with changes in temperature.

2. A heater unit comprising a carbonaceous
resistance element, a silicon carbide sheath
120 enclosing said element, said sheath and ele-
ment being positioned with a slight space
therebetween so as to be free to expand and
contract independently of one another.

3. A heating element consisting of a car-
bonaceous resistance element, terminals se-
cured to said element and a monolithic sili-
con carbide sheath enclosing said element and
terminals and being separate from said re-
sistance element so as to be free to expand
125

and contract independently of said element and terminals.

4. A resistor comprising a carbonaceous resistance element incased in a monolithic mass of silicon carbide, the silicon carbide next to the surface of the resistance element being recrystallized, said mass of silicon carbide being separate from said resistance element so as to be free to expand and contract independently of said resistance element.

5. A carbon resistance element, a silicon carbide sheath enclosing the same and spaced therefrom sufficiently to permit relative expansion and contraction of said element and sheath and fused borax at the outer surface of said sheath for rendering the sheath impervious to gas.

6. A heating element consisting of a carbon resistance element, conducting terminals secured thereto and a monolithic mass of silicon carbide forming a sheath enclosing said element and terminals, said mass being supported in contact with the terminals near their outer ends and being spaced from other portions of said terminals and from said resistance element sufficiently to permit independent relative expansion and contraction of said mass and said element and terminals.

7. A heating element consisting of a carbon resistance element, conducting terminals secured thereto, a monolithic mass of silicon carbide forming a sheath enclosing said element and terminals, said mass being supported in contact with the terminals near their outer ends and being spaced from other portions of said terminals and from said resistance element sufficiently to permit independent relative expansion and contraction of said mass and said element and terminals and fused borax at the outer surface of said sheath for rendering said sheath impervious to gas.

8. A method of forming a resistor which consists in coating a carbon resistance element with a readily fusible material, moulding around the coated element a mixture of crushed silicon carbide grains and a temporary binder, slowly heating the resistance element by the passage of current therethrough until the entire mass has attained a white heat.

9. A method of forming a heating element which consists in connecting conducting terminals to a zigzag graphite resistance element, coating said resistance element and the inner portions of said terminals with a readily fusible material without filling the slots between sections of the resistance element, moulding around said coated element and terminals a mixture of coarse and fine silicon carbide grains together with a binder comprising borax, slowly heating the mass to a white heat by passing current through the resistance element whereby the silicon car-

bide grains are converted into a monolithic mass of recrystallized silicon carbide, which is in contact with the outer portions of the terminals and is spaced sufficiently from the inner portions of said terminals and from the resistance element so as to permit relative expansion of said terminals and element and said mass of recrystallized silicon carbide, and whereby said borax forms a sealing medium at the outer surface of said mass of recrystallized silicon carbide.
